James B. Leftwich, INVENTOR
BY *Victor J. Evans*
HIS ATTORNEY

UNITED STATES PATENT OFFICE

JAMES B. LEFTWICH, OF CHICAGO, ILLINOIS

VALVE-BUSHING REMOVER

Application filed March 11, 1929. Serial No. 346,163.

This invention relates to certain novel improvements in valve bushing removers and has for its principal object the provision of an improved construction of this character which will be highly efficient in use and economical in manufacture.

The salient object of my invention is to provide an arrangement which will include portions that may be disposed below a valve bushing in order to facilitate the removal thereof.

Another object of the invention is to provide a device of the above named character which will include an arrangement such that an impact may be provided on the member having portions disposed below the valve bushing so that these impacts may facilitate the removal of the valve bushing.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a view depicting a preferred form of construction for my invention in operative position;

Fig. 2 is a view drawn to an enlarged scale of the embodiment of my invention illustrated in Fig. 1; and

Fig. 3 is a transverse sectional view taken substantially on the line 3—3 on Fig. 2.

In the accompanying drawing wherein I have illustrated a preferred form of construction of my invention 10 indicates a body in which a passage 11 is formed that has a sleeve 12 retained therein. The end 13 of the sleeve 12 is spaced on the edge of the body 10 and a valve bushing or seat 14 is disposed in this space and includes portions which extend over the passage 15 through the sleeve 12.

My improved tool comprises a main portion 16 which in the present instance is in the form of a cylindrical rod and which includes a bifurcated end portion 17. On the ends of the arms 18 and 19 of the bifurcated end portion and on the outwardly disposed

sides of either arm I provide shoulders 20 and 21. At the end of the rod 16 opposite the bifurcated end is a head or collar 22 and above the head or collar 22 is a suitable handle construction 23. Mounted so as to be 55 slidable on the rod 16 axially thereof is a sleeve 24 which includes enlarged end portions 25 and 26 and this sleeve 24 is intended to provide a knocker or impact member that is employed in the manner now to be set 60 forth.

In use my improved tool is arranged so that the bifurcated end portion 17 is extended into the passage 15, the arms 18 and 19 of the bifurcated end portion 17 being bent inwardly to permit passage past the valve bushing 14. The arms 18 and 19 are preferably innately resilient and will therefore tend to reassume a position similar to that depicted in Fig. 2 and, therefore, by moving 70 the tool upwardly the shoulders 20 and 21 may be brought into engagement with the portions of the valve bushing extending over the passage 15. The handle 23 is then gripped and by moving the sleeve or knocker 24 upwardly so as to cause an impact on the shoulder 22 the valve bushing 14 may be moved from its seat, it being understood that the sleeve 24 will be reciprocated so sufficient impacts have been impressed on the 80 head 22 to loosen the valve seat 14. It is apparent from the foregoing description that I have provided a device which is of a relatively simple and inexpensive construction and yet it may effectively be employed for the 85 removal of valve bushings and the like.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the 95 appended claim.

Having thus described my invention, what I claim as new and desire to protect by Letters Patent is:

In a device of the class described, an elong-

gated body member, said body member having a bifurcated end portion providing arms, shoulders on said arms, said body member having an enlarged head portion formed thereon at the end opposite said bifurcated portion providing an annular shoulder, a handle on said body member outwardly of said head portion, a sleeve on said body member adapted for reciprocal movement over said member, said sleeve having enlarged end portions providing shoulders whereby when said sleeve member is moved in one direction over said body member one of said last-mentioned shoulders will have abutting engagement with the shoulder on said body member and when said sleeve member is moved in an opposite direction over said body member the other of said last-mentioned shoulders will compress said arms inwardly.

20 In testimony whereof I affix my signature.
JAMES B. LEFTWICH.
